(57) **CLAIM**

The ornamental design for a cocktails smoker, as shown and described.

DESCRIPTION

FIG. 1 is a top perspective view of the cocktails smoker showing my new design;

FIG. 2 is a bottom perspective view thereof;

FIG. 3 is another bottom perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is an exploded perspective view of the cocktail smoker with the top portion shown separated from the base. The broken lines shown in the drawings are included for the purpose of illustrating portions of the cocktails smoker that form no part of the claimed design.
